UNITED STATES PATENT OFFICE.

SYLVANUS D. LOCKE, OF HOOSICK FALLS, NEW YORK.

GRAIN-BINDER.

SPECIFICATION forming part of Letters Patent No. 423,524, dated March 18, 1890.

Application filed June 24, 1884. Serial No. 135,860. (No model.)

To all whom it may concern:

Be it known that I, SYLVANUS D. LOCKE, of Hoosick Falls, in the county of Rensselaer and State of New York, have invented certain new and useful Improvements in Grain-Binders, of which the following is a specification.

My invention relates to mechanism for automatically binding grain; and it consists in the employment, at the delivery end of the elevator or other carrier delivering grain into the binding-receptacle or within reach of the gathering or the binding mechanism, of a pair of stripper-rolls one or both being fluted or armed with fingers or teeth for the purpose of positively delivering or forcing the grain into the binding mechanism, and driven by a system of gearing located on the machine in front of the grain and actuated by a driving-roll of the elevator, or a shaft in practically the same relative position, and itself driven at the rear of the elevator; in the employment, in connection with the delivery mechanism, of a vibrating separator lever or arm intermediate between the delivery and the binding mechanism, acting in such manner that the separator-arm freely allows the accumulated gavel to pass beyond it to the binding position and then is forcibly returned to its former position to separate the grain near the delivery mechanism from the bundle gathered in binding position or receptacle and hold the former positively back as the bundle after being bound is ejected from the machine, thereby securing a complete separation of the bundle from the entangled stream of grain; in the employment, intermediate between the delivery and the binding mechanism, of a trip and separator lever or arm that, under pressure of the grain accumulated by the delivery mechanism, first yields outwardly a fixed distance to engage a clutch to start the binding mechanism, then yields freely to allow the accumulated grain to pass to the binding position, and is then positively returned to and is held in its first position to prevent the stream of grain from following the gavel as it is carried to the binding position and afterward ejected from the machine; in the arrangement of two rock-shafts, one below and one above the grain, one supported on and fixed to the har-

vester-frame and having secured thereto at its inner end a disengaging-pawl, and at its outer end, preferably at the "butts" of the grain, a fixed lever-arm, the other supported on and fixed to the frame of an adjustable binding mechanism, and having secured thereto at its inner end a trip-lever and at its outer end a lifting or holding-up lever-arm sliding thereon, (on a feather or spline,) acted upon by a ledge on the main gear and held fixed as to the harvester-frame by a yoke or stops extending therefrom and connected to the other lever-arm, whereby the pawl may always remain with its clutch that controls the binding mechanism fixed on the harvester-frame, while the trip-lever is fixed as to the binding mechanism and accompanies the latter as it is adjusted forward and back on the harvester-frame to the varying length of the grain; and in the various other combinations and details of construction hereinafter pointed out and claimed.

In the drawings, Figure 1 is a rear elevation of so much of a harvester-platform and elevator, with automatic binding attachment, as is necessary to show my invention; Fig. 2, a front view of a portion thereof to show the gearing for driving the elevator-aprons and the stripper-rolls, and also showing a part of the tripping devices; Fig. 3, a top plan view of the binding attachment, including the elevator-head; Fig. 4, a plan view of the harvester-gearing beneath the binding-table, and also so much of the binder-gearing as lies beneath said table; Fig. 5, a rear elevation of the binding attachment with the binder-arm down and moving toward the band-securing devices; Fig. 6, a like rear elevation, with the binder-arm farther advanced and at the point from which it commences its return movement to its position of rest; Fig. 7, an elevation from the stubble side of the binding attachment with the binding-table in section and the overhung bracket of the post-frame, and the parts which it carries omitted; and Figs. 8 and 9, details, respectively, of an adjustable cord-guide which I propose to employ and of the construction at the rear head of the elevator to carry the grain free of the sprocket-wheel.

In the harvester A is the rear sill of the elevator-frame spliced to the rear platform-sill

A' by a metallic strip a , which affords a bearing for the gudgeon of the inner platform-apron roller and a support for the idle sprocket-wheel common to these machines.

- 5 A² is the main wheel turning loosely upon a short axle, which at its ends has small pinions running in segment rack-standards A³, and is carried up and down along the racks by a worm-wheel a' and worm-shaft a^2 , 10 extending up rearwardly toward the driver's seat, which is intended to be located behind the elevator in this type of machines, and having at its extreme or outer end a crank a^3 , whereby it may be turned to carry the axle 15 along the standards, and thereby raise or depress the main wheel relatively to the main frame to adjust the latter. The main wheel drives a prime pinion-shaft B, which, by means of a beveled gear b , having two concentric 20 series of teeth, meshes with and drives, respectively, the beveled pinion b' at the inner end of the shaft B', having crank b^2 to actuate the cutter and the beveled pinion b^3 at the inner end of the driving sprocket-wheel shaft B², 25 the cutter-crank-shaft pinion engaging with the outer series of teeth on the beveled gear for speed, and the sprocket-wheel pinion engaging with the inner series of teeth to gain power.
- 30 C C' are the inner and outer rear elevator-struts, and C² the lower elevator-apron; C³, a frame overhung from the front of the machine by means of a supporting-bar c at its head for the purpose of carrying the upper elevator-apron, while allowing the heads of long grain to project through the throatway left at the rear of the machine.

As thus far described, the component features of the harvester do not differ essentially 40 from those before alluded to. In the present case, however, I mount the pulleys at the upper end of the elevator-aprons in such manner that these aprons terminate slightly short of the head of the elevator itself, the upper 45 apron preferably projecting somewhat beyond the end of the lower, and beyond them place stripper-rolls c² c³, the first for the upper and the second for the lower apron, which rolls fill the space between the ends of the 50 aprons and the head or delivery point, and, being positively driven in the proper direction, serve to take the grain as it is brought up between the aprons and carry it onto the grain-chute. If they were for the purpose of 55 stripping simply, they might be made smooth; but with regard to their relations to the automatic binding apparatus about to be described, one or both will be made toothed or fluted, in order that they may not only act as 60 strippers, but also as packers to press the grain forward against the starter or trip-lever, or whatever tripping devices may be used. Preferably the upper only is furnished with flutes or teeth, as the lower, if so provided, may 65 wind the grain around itself. They may be placed so that their axes will be in ascending planes carried through the axes of the

upper and lower drums of the aprons which they respectively strip, in which case the passage-way formed by the elevator would be 75 straight clear to its head, as in harvesters heretofore used; but it is better, and permits a more effective action with reference to the binding mechanism, to place them, respectively, slightly below said planes, thus causing the passage-way to assume a practically horizontal position at the head of the elevator, as shown; or they may even be placed so low that the passage-way will curve downward to connect with the grain-chute at the discharge or delivery point.

For the purpose of driving the elevating and stripping mechanism, and also the platform-apron, and also for the purpose of removing the driving-chain at the rear of the 85 machine from its former position, where it interfered with the purpose of the open throat-way at the rear of the space between the two elevator-aprons, I have adopted the following arrangement of gearing: From beneath 90 the sprocket-wheel D at the rear end of the shaft B², driven from the main wheel, as before described, or in any other suitable manner, I lead the chain directly to a point beneath the sprocket-wheel D' on the gudgeon 95 of the inner platform-apron roller. Passing it up over this wheel, I carry it beneath the idle sprocket-wheel D², located in the usual place, thence up and over the sprocket-wheel D³ on the gudgeon of the upper drum or 100 roller of the lowest elevator-apron, finally from this returning it over the outer periphery of the driving sprocket-wheel to its starting-point. Thus it is laid in such position that it will nowhere interfere with the open 105 throatway while still driving the parts in the proper direction.

On the front gudgeon of the driven drum of the lower elevator-apron is keyed a pinion d , which meshes with and drives a spur-wheel d' , turning on a stub axle or pivot fixed to the elevator-frame or some suitable support, and having no function except to transmit motion, which it does, in the first instance, by driving the pinion d^2 of the lower stripper, and being set out from the frame or support sufficiently to admit between itself and the wall of said support the pinion d^3 of the upper drum of the overlying elevator-apron. A long idle-pinion d^4 , also driven by it, meshes back 110 with said interlying pinion to drive the apron, and forward with another pinion d^5 on the gudgeon of the upper stripper, whereby the latter, like the foregoing effective instrumentalities, is positively driven. So far as the 115 agency of these front and rear gudgeons in driving these instrumentalities is concerned, they are in effect a shaft coincident with the axis of the roller which they carry, and may be considered as representing any shaft occupying practically the same relative position.

Heretofore, where I have used the open throatway at the rear, the teeth of the sprock-

et-wheel at the head of the lower elevator-apron have been permitted to project beyond the supporting-surface for the grain at this point, as their tendency naturally seemed to be to assist the grain onward toward the chute; but they prove also quite, if not more, liable to clog and tangle with it and to thrash out the full ears with which they are constantly coming in contact, and the chain is permitted to close upon and carry down these ears and the stalks. Therefore in this machine the casting D⁴, bolted to the rear elevator strut or board and supporting the worm-shaft of the main-wheel-adjusting apparatus, is carried up to afford a bearing for the axle of this sprocket-wheel, and above the axle widens and terminates in an outwardly-extending flange d⁶, concentric with the axle and on or slightly beyond the crest-line of the teeth, thus serving to support the grain and carry it past the wheel without contact either with teeth or chain. The flange is intended to practically bridge the gap between the teeth of the wheel and the rear face of the elevator-strut or of the body of the casting, which is necessarily of appreciable width. It may, however, be omitted if this space is otherwise closed, or even when it is not, though to less advantage.

30 The extension of the casting D⁴ alone, without further change over the ordinary construction, would present a shoulder projecting above the rear board to obstruct the grain, so that the object sought would be neutralized; hence a guide-piece D⁵ is secured to this rear board, inclining up above the edge thereof until it abuts against the casting and forms a flush joint with the flange, so that the grain as it is carried up is gradually and easily lifted to the crest of this flange.

40 The binder-frame upon which I have chosen to exhibit my improvements and to which some of them are more especially applicable is composed, as in machines already well known in the art, of a tubular post E, either at the front or rear of the table, preferably the front, a tubular arm E' subtending the table from this post to the neighborhood of the slot for the play of the binding-arm, and a tubular bracket E² overhanging the table to practically the same distance. These three members, by means of diagonal connecting-webs at the meeting points, are readily made as a single casting, which is supported upon feet e, running upon removable rods or guides e' mounted in brackets e² e³ from the end sill, one of which brackets in each pair—to wit, the bracket e³—is cupped or flanged to support the feet when the rods are withdrawn, whereby not only is the frame readily adjusted back and forth to compensate for varying lengths of grain, but the machine easily dismantled without necessitating a large force of assistants.

50 A standard e⁴ from the inner end of the tubular subtending arm affords means for the attachment of the stock e⁵, which carries the

knotter or twister and band-holder, with such other immediate accessories to the knotting or twisting devices as may be desirable. The head of this stock is broad and flat, affording a seat or bracket for the support of the outer part of the binding-table E³, and on the vertical post opposite is a horizontal offset e⁶, also affording a seat or bracket for the support of said table at the adjacent corner, a single bolt to each bracket serving to bind the table to the frame, whereby when these two bolts are removed it is entirely disconnected therefrom.

At its inner edge, adjoining the elevator-frame, the binding-table is provided with metallic saddle-pieces e⁷, two or more in line with each other, having squared grooves with vertical sides, and which sit over and snugly embrace ways e⁸, squared or of plate metal, also presenting vertical sides, secured to the elevator-frame parallel with the guide-rods upon which the binder-frame moves, so as to form the inner track for the back-and-forth adjustment of the binding devices. A further purpose served by this arrangement is that the ways and saddle pieces serve to tie the binder-frame and whole binding attachment to the harvester, dispensing with the brace-rods or tie-pieces heretofore commonly stretched from the overhung bracket to a beam or carriage thereon above the elevator-head, and that they permit the binding-table to be lifted off from above the mechanism which it covers whenever the two bolts fastening it to the binder-frame are removed, instead of requiring it to be slid off endwise. The table has the usual ledges E⁴ secured to it and extending along the slot for the play of the binder-arm, and also up toward the head of the elevator to lift the waist of the gavel and allow the band material to be carried cleanly beneath, and is braced at the outer end of the slot by an inverted bridge E⁵, permitting the point of the binder-arm to sweep entirely through in ejecting the bound sheaf.

Several of the features thus far enumerated look toward the rapid and facile dismantling of the binder. To completely work out this object, the lever F, by which the adjustments to compensate for length of grain are made by the driver or attendant, is connected with the binder by means of a hooked link F', pivoted to the shank of said lever and catching into an eye-plate f, bolted to the under side of the table at its rear end. This lever, or a similar lever for the purpose, has usually been located at a distance from the table, mounted upon a horizontal pivot, and conveying its power by means of a rock-shaft or series of connecting-links and elbow-levers to the table. In the present instance it is placed upon an inclined pivot f', secured to the outer elevator-strut at the rear of the machine and at nearly right angles to the slope of such strut, so that the lever vibrates in a plane nearly parallel to such strut, thus

bringing the hand-hold up within the reach of the driver in his seat at the rear of said elevator and dispensing with all intermediate connections except the single link, which can be readily hooked into or unhooked from the eye-plate, so as to entirely detach the lever from the table when the latter is to be taken off or the binder attachment removed.

Coming now to the active mechanism of the binder, a pinion G, fixed to the sprocket-wheel shaft before mentioned, drives a spur-wheel G', loosely mounted on a counter-shaft G², but capable of being locked thereto by a sliding clutch-half G³, pressed constantly toward the wheel by a coiled spring g, so that unless forcibly held away it will engage with the wheel and cause the shaft to turn. Upon the sliding half of the clutch is a peripheral flange g', which upon the face toward the wheel at one point presents an incline g², terminating finally in a stop or shoulder g³, the purpose of this being to permit the trip-dog hereinafter described to force the sliding half away from the wheel, and, finally, by coming against the stop when the clutch is fully disengaged, to lock the shaft positively against motion in the direction in which the wheel is turning. This counter-shaft G² is mounted in brackets on the harvester-frame, and has a long groove extending between two of these brackets, whereby the sliding pinion g⁴, which communicates motion to the detachable parts of the binder, is splined to said shaft and permitted to slide longitudinally thereof between the bearings as the binder is adjusted. A gear and cam wheel H, similar to those heretofore employed by me for the purpose of operating the twisting or knotting and holding and cutting mechanisms, except in a single feature hereinafter explained, engages with the sliding pinion, being itself mounted at the end of a horizontal shaft running through the tubular subtending arm of the frame and connecting by beveled gears with a second shaft running through the vertical tubular post, this shaft in its turn connecting by delay-gearing with a third shaft, turning in an overhanging arm or bracket of the frame, the last-named shaft being the binder-arm shaft, and the purpose of the delay-gearing or stop-motion is to halt the binder-arm opposite the band-uniting mechanism for a proper period, holding it stationary there. The binder-shaft is shown as provided with an adjustable crank H', such as referred to by me in an application heretofore filed—to wit, on the 17th day of April, 1883, Serial No. 92,021—and the binder-arm H² is link-suspended at its heel end and has the shape and is operated—except in the matter of being automatically tripped—as in said application. Beneath the binding-table is also hinged a cam-block H³, supporting at its outer end an elastically-yielding compressor H⁴, which is carried up through the slot in the binding-table and held stationary there for a proper

interval, and then permitted to descend by means of a couple of rollers h h', mounted upon the ends of crank-arms h² h³ from the inner or rear end of the shaft turned by the gear and cam wheel. These parts, and others not by themselves novel in the present application, are referred to for the purpose of explaining the operation of the improvements and on account of certain particular combinations herein-after pointed out, into which they enter as effective elements or as representatives of well-known equivalents.

A bar I is bolted to the overhanging bracket at its inner end and extends over the binding-table nearly or quite to the head of the elevator, being shown herein as passing slightly above the overhanging support of the upper elevator-apron, but not attached thereto. This bar is braced from the bracket by a diagonal rod I', which, by means of jam-nuts, may be made to adjust its free end. The primary purpose of the bar is to afford a bearing above the binding-table for the inner or rear end of a rock-shaft I², the other end of which is borne in a bracket I³ at the head of a standard rising from the front outside strut of the elevator-frame, or in any other suitable manner firmly secured to the frame. The rear bearing of the rock-shaft of course moves with the adjustment of the binding-table and the rock-shaft moves with it. It therefore slides in the front bearing. This front bearing is split or forked to receive and hold against lateral displacement the hub of an arm i, which, by means of a spline-and-groove connection with the shaft, is caused to partake of its rocking motion and act as a crank arm or lever. The outer end of this crank-arm is connected by means of a link I⁴ with a second crank-arm i' from the end of the rock-shaft I⁵, mounted beneath the binding-table and passing rearwardly from its first bearing i² on the outside elevator-strut to a point opposite the tripping-clutch before alluded to, where it is received in a second bearing i³, formed in the bracket I⁶, bolted for convenience to one of the inclined brace-bars of the outer struts of the elevator-frame. This shaft, having both bearings upon the elevator-frame, is of course free from longitudinal movement. Nearto its rear bearing it has secured to it a dog i⁴, so arranged that its nose vibrates in a plane passing between the sliding and fixed halves of the tripping-clutch. Thus when the dog is depressed by the movement of the rock-shaft, however caused, it will enter between the face of the spur-wheel or the hub formed thereon and the peripheral flange on the sliding half of the clutch, and as the two, previously locked together, continue to turn it will strike the incline on said flange and, riding up it, will force the sliding half away, until finally the clutch is disengaged and the nose of the dog has come in contact with the stop on the flange, locking the counter-shaft against further movement.

The most convenient means to accomplish the depression of the tripping-dog is a spring t^5 , seated between a shoulder on said dog and an offset from the bracket in which the 5 rock-shaft is borne, and having sufficient strength to move both rock-shafts and their attachments and any additional strength that may be found necessary or desirable. It is evident that when the dog is lifted from 10 between the sliding and the fixed half of the clutch an immediate engagement will ensue and the binder be started by the harvester-gearing; and for the purpose of causing such lifting of the dog and consequent engagement of the clutch by the accumulation 15 of the gavel, I mount upon the inner end of the first or upper rock-shaft—the one which slides with the binder—an arm K, properly curved and depending, so that its nose reaches 20 alongside, or nearly so, one of the two grain-ledges on the binding-table at any suitable point, either at the junction of said table with the grain-chute or somewhere along said chute or the table. This arm will receive and 25 stop the grain fed inward by the stripping and packing rolls, and being secured to the shaft by a connection which sooner or later is rigid will rock the latter whenever the accumulation of the grain may become sufficient 30 to force it to yield. This rocking movement will be simultaneously communicated to the lower rock-shaft and thereby the tripping-dog raised and the clutch caused to engage. In case the clutch-shaft revolves once 35 to each revolution of the binding mechanism, the disengaging or trip dog needs nothing but the trip-lever and connecting devices to disengage and the spring to engage it; but when the clutch, as in the present 40 gearing, revolves several times during one revolution of the binding mechanism, other instrumentalities will have to be employed to prevent the binding mechanism being stopped at each revolution of said clutch. To 45 this end a lifting or holding lever K' is employed, having in this instance where the binder is adjusted a hub feathered to the lower rock-shaft to slide longitudinally thereof, but partake of its rocking movements, 50 and forked to embrace the gear and cam wheel (the main gear of the binder) so as to accompany the binder-frame in its adjustments. One arm k of the fork is prolonged to come in the path of a ledge k' on the face 55 of the gear and cam wheel, so that immediately after the clutch has been tripped and the binder started the ledge comes beneath the now raised arm and prevents it from falling until the revolution of the gear and cam 60 wheel itself is nearly completed, when the ledge passes out from beneath the arm and permits it, and consequently the trip-dog, to fall in time to disengage the clutch to terminate with the full revolution. 65 If the arm K, hereinafter called the "trip arm" or "lever," should be rigidly secured to its rock-shaft, it is evident that the binding

mechanism would be started by the accumulation of the same quantity of grain under like conditions every time, and that there 70 would be no control over the size of the gavels and the sheaves which they form. The conditions varying, as from wet to dry, the size might vary and would be in no way subject to the judgment of the attendant. It is 75 preferable, therefore, to mount the trip-lever loosely upon its rock-shaft and to key to this shaft a segment or other plate K², having a series of perforations k², one above the other, either arranged concentric with the axis of 80 the shaft, as shown, or in a straight or zigzag manner, as may seem advisable. A thumbscrew or bolt, or other stop k³, is adapted to be inserted into any one of these holes, and by inserting it nearer to or farther from the 85 trip-lever in its normal depressed condition the latter will rise to a less or greater distance before it becomes rigidly engaged with the shaft so as to move it and effect the tripping action, thus hastening or postponing this action and diminishing or increasing the size 90 of the bundles.

In some machines and for some purposes the tripping arrangement, as thus far described, will be sufficient. I, however, think 95 it best to cause the trip-lever to act also as a divider or cut-off, saving the use of an independent divider and cutting off at the precise point where the accumulation of another gavel is to commence. To this end an arm K³ 100 is pivoted to the supporting-bar, bolted, as before stated, to the overhanging bracket, and is at one end connected by a link k⁴ with the trip-lever somewhat inside the pivot of the latter. The other end is bent downward over 105 the binder-arm shaft and provided with a straight inclined shoe k⁵ and a segmental shoe k⁶. A cam K⁴ is mounted upon or cast solid with the hub of the binder-arm crank, or else keyed to the shaft just inside that hub 110 beneath the bent end of the pivoted arm. This cam has a segmental trackway k⁷, corresponding in length to the distance which the shaft travels in carrying the binder-arm from the point in which the grain should be 115 cut off around and up to near its position of rest at the moment the binder is thrown out of gear.

At the inner end of the segmental track is a roller k⁸, sunk in a recess in the cam, so as to expose only a portion of its periphery, and as the cam revolves this roller strikes the inclined track on the end of the pivoted arm, lifting the end of the arm, and in its passage over the track entirely forcing the trip-lever down, 120 so that it enters and divides the grain alongside of or in the cleft made by the binding-arm, which has then reached the point where the trip-arm rests when down. At this moment the curved track of the cam engages 125 with the curved shoe of the arm and locks the trip-lever in position until at least the bound bundle has been discharged and in practice a little later. When the binder-arm 130

has reached its position of rest, (indicated in Fig. 1,) the segment has passed out of engagement with the curved track, and the trip-lever is free to yield again to start the binder.

- 5 To prevent the grain from passing beyond the reach of the trip-lever and acting as a separator, while the binder-arm continues its motion and before the trip-lever is fully down, a spring L is attached to that one of the 10 grain-ledges alongside which the end of the trip-lever comes or to the grain-chute, so as to lie close to the path of the trip-lever and at a sufficient height to allow it to be bent concentrically with the axis of the lever and 15 to lie throughout its whole length within the trajectory of the point of the latter. This spring holds back the grain that follows the binder-arm as the bundle is being carried into position, so that all behind the arm is 20 embraced and swept back by the trip-lever in its descent. A second spring L' is attached to the grain-chute near the rear of the machine and somewhat above the spring just mentioned for a slightly-different purpose—that is, it has been found in experience 25 that when the bundle is ejected some of the grain, entangled as to the tops, is very apt to follow the bundle. Therefore this second or auxiliary spring is put in to catch and hold 30 back this grain, and also in connection with the trip-lever to hold the accumulating gavel from dropping down and sliding endwise from the machine, for this purpose being so placed that it comes in the path of the heads 35 of grain. It is shown as secured to the harvester-frame; but it may be attached to the rear of the table at its upper portion, provided that this part of the table extends sufficiently high.
- 40 Over the front of the table inside the wind-board L² is placed the shield or hood L³, extending from the head of the elevator nearly to the overhanging bracket of the binder-frame and curved downward at its extreme 45 outer end to near the gearing at the joint between the bracket and vertical post, that loose grain may not become entangled with the delay-gears and clog or render uncertain the action of the machine. It serves also as 50 a hood or cover to keep the grain from rising too high in the receptacle or shooting over the binding mechanism.

It has been my practice formerly to mount the cord-box M on a sliding carriage supported upon the overhanging bar which receives the weight of the upper elevator-apron frame, and to make this carriage also the inner point of attachment for the brace-rods which stayed the overhung bracket of the 55 binder-frame. Now that these brace-rods are dispensed with by the use of the binding-table as a brace to the frame, as heretofore explained, the sliding carriage is omitted and the cord-box bolted to the overhanging bar 60 through the interposition of a bracket m, one arm of which is secured to the box and the other to the bar; but as the binder is adjusted

the direction of the cord led from the box might vary without some compensating device additional to the guides heretofore used, 70 and the binder-arm, which does not receive the cord through an eye in its point, but catches over it at each binding operation, might under some adjustments fail to catch or else catch between a guide and the box. 75 For this reason I form guide-eyes m' m' in the end of the arm which supports the upper tripping rock-shaft, carrying this end up close to or immediately above the elevator-head. Two eyes in line with each other transversely 80 to the overhanging bar are employed, as one eye must be near the trajectory of the point of the binder-arm, and if receiving the cord directly from the box might permit interference between itself and said box, and by using 85 two eyes the rearmost can be set back in line with the cord-box and always hold the cord therebetween out of reach of the binder-arm. The position of the eyes is advisably made capable of adjustment, and this may be done 90 by means of the oblique brace-rod between the supporting-arm and the overhung bracket or otherwise by employing the construction shown in Fig. 8, wherein said eyes are formed in an independent plate M', connected to the 95 supporting-arm by slot and screw M² M³, the contracting faces of the two pieces being smooth or roughened, as desired.

It will be observed that the binder-arm in the present invention has two points of defined rest—the first when the binder comes to a full stop by the disengagement of the clutch, and the second after the accumulation of grain has tripped and started the binder and while all other parts of the binder are 105 working, said latter stop or rest being caused by the delay-gears at the moment the binder-arm is opposite the band-uniting devices and while these devices are in active motion.

I claim—

1. The combination, substantially as hereinbefore set forth, with the elevator-carriers, of stripper-rolls at the head of each carrier, and a system of gearing located in front of the machine and actuated by a driving-roll 115 of the elevator, which roll is itself driven at the rear of the elevator.
2. The combination, substantially as hereinbefore set forth, with grain-delivery mechanism and automatic binding mechanism, of a trip-lever which yields before the incoming grain to start the binding devices, and mechanism whereby said lever is caused to return to position after the binder-arm has gathered the gavel, to separate the incoming stream 125 from said gavel.
3. The combination, substantially as hereinbefore set forth, of the two rock-shafts, one above and the other below the binding-table, the connecting-link, the clutch and trip dog, 130 the trip-lever, the lifting-arm, and the ledge on the main gear.
4. The combination, substantially as hereinbefore set forth, of the sliding binder-frame

and table, the upper rock-shaft sliding through its lever-arm, the lower rock-shaft on the harvester-frame, the clutch and trip-dog, the lifting or holding-up arm feathered to the lower 5 rock-shaft to slide therealong, and the main gear with its ledge acting upon a fork or finger of said holding-up arm.

5. The combination, substantially as hereinbefore set forth, of the sprocket-wheel on 10 the drum at the rear head of the lower elevator-apron, the chain, the flanged casting, and the guide-board.

6. The combination, substantially as hereinbefore set forth, of the separator-arm and 15 its adjacent separating-spring.

7. The combination, substantially as hereinbefore set forth, with the grain-chute or upper part of the grain-table, of the spring to retard and support the heads of the grain, 20 and the trip-lever arranged to close the passage at a lower point along the chute.

8. The combination, substantially as hereinbefore set forth, with the binder-arm, cord-box, and supporting-bar from the overhung bracket, of an adjustable guide-plate mounted 25 on said bar and having two eyes.

9. The combination, substantially as hereinbefore set forth, of the binder-frame sliding on ways at the outer or stubble side of the 30 harvester and provided with two seats, the grain-table secured to said seats by a bolt to each, the squared ways on the elevator-frame, and the saddle-runners on the under side of said table, whereby the table can be lifted 35 directly off by unfastening the two bolts, but serves to brace the frame while the bolts are in place.

10. The combination, substantially as hereinbefore set forth, with the trip-lever, of the arm which supports its rock-shaft, the pivoted depressing-arm link connected to said lever, and the cam on the hub of the binder-arm crank or its shaft. 40

11. The combination, substantially as hereinbefore set forth, of the binder-frame mounted on ways at the outer or stubble end of the harvester, and the grain-table secured thereto and carrying at its inner side saddle-runners which embrace squared or equivalent ways attached to the elevator-frame and thereby 45 brace the binder-frame.

12. The combination, substantially as hereinbefore set forth, with the binding-table and overhung bracket, and with the gearing at the junction of said bracket and the vertical 50 post, of the shield covering the front end of the table and protecting said gearing. 55

13. The combination, substantially as hereinbefore set forth, of the bracket-arm, the bar for supporting the upper tripping rock-shaft 55 extending therefrom, and the diagonal brace-rod connecting the two.

14. The combination, with the sliding trip-shaft, of the lever splined thereto and held against lateral motion by the forked bearing. 60

15. The combination, substantially as hereinbefore set forth, with the disengaging-dog, of its holding-up arm, and the ledge on the main gear, whereby said arm is retained during several revolutions of the clutch. 65

SYLVANUS D. LOCKE.
